(57) **CLAIM**

The ornamental design for the portion of a ceiling fan
housing, as shown and described.

DESCRIPTION

FIG. 1 is a perspective view from below of a portion of a
ceiling fan housing in accordance with my design;

FIG. 2 is an enlarged perspective view from below of the
portion of a ceiling fan housing in accordance with my
design;

FIG. 3 is a bottom plan view of the portion of a ceiling fan
housing in accordance with my design; and,

FIG. 4 is an enlarged representative side elevation view of
the portion of a ceiling fan housing in accordance with my
design.

The broken lines showing environmental structure are for
illustrative purposes and form no part of the claimed design.
